(57) **CLAIM**

The ornamental design for a beach short as shown and described.

DESCRIPTION

FIG. 1 is a front elevational view of beach shorts.

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a right side perspective view thereof;

FIG. 8 is a left side perspective view thereof;

FIG. 9 is a front perspective view of the beach short shown with the outer layer on the right side of the beach short depicted in a flipped configuration; and,

FIG. 10 is a front perspective view of the beach short shown with the outer layer on the right side of the beach short depicted removed.

The broken lines depict portions of the beach shorts that form no part of the claimed design.

1 Claim, 10 Drawing Sheets
